(57) **CLAIM**

We claim the ornamental design for the indented baseball, as shown and described.

DESCRIPTION

FIG. 1 is a perspective view of the indented baseball, showing our new design;

FIG. 2 is a side elevational view thereof, the opposite side view being identical, the top and bottom plan views are identical to the side views except for the stitching which is a mirror image to the stitching on the side views; and,

FIG. 3 is an end elevational view thereof, the opposite end elevational view being identical.

1 Claim, 3 Drawing Sheets

FIG. 1

FIG. 2

FIG. 3
